UNITED STATES PATENT OFFICE.

ERIK GUSTAF NICOLAUS SALENIUS, OF STOCKHOLM, SWEDEN.

THRASHING-MACHINE.

SPECIFICATION forming part of Letters Patent No. 469,871, dated March 1, 1892.

Application filed September 28, 1889. Serial No. 325,365. (No model.) Patented in Norway November 17, 1888, No. 1,222; in England November 21, 1888, No. 16,962, and in Austria-Hungary March 17, 1889, No. 48,364 and No. 9,431.

To all whom it may concern:

Be it known that I, ERIK GUSTAF NICOLAUS SALENIUS, a subject of the King of Sweden, residing at Stockholm, Sweden, have invented 5 certain Improvements in Thrashing - Machines, (for which patents have been granted in Great Britain, No. 16,962, dated November 21, 1888; in Austria-Hungary, No. 48,364 and No. 9,431, dated March 17, 1889, and in Norway, No. 1,222, dated November 17, 1888,) of which the following is a specification.

My invention relates to machines for thrashing and separating grain, and particularly to that portion of the machine which shakes and carries away the straw when thrashed; and the object of my invention is to provide a simple and effective straw-shaker which will effectually shake out all the loose grain.

My invention will be fully described hereinafter, and its novel features carefully defined in the claims.

In the accompanying drawings, illustrative of my invention, Figure 1 is a side elevation, mainly in section, of a thrashing-machine provided with my improvements. Fig. 2 is a plan of the same, and Fig. 3 is a fragmentary side elevation showing a part of the side opposite to that shown in Fig. 1. Figs. 4 and 5 are respectively a side elevation and a plan, on a large scale, of the preferred form of chain employed in the shaker.

A and A' represent, respectively, the major and minor inclined sides of the V-like grain-receiving chamber B in the machine.

35 a is the cylinder, and y the feed-hopper. The grain falling to the bottom of chamber B is carried up over the inclined side A by an endless carrier or conveyer b. (Clearly illustrated in Fig. 1.) On reaching the top of side

40 A the grain falls into the compartment B', where the winnowing mechanism is situated.

Mounted on the sides c of the machine is a frame composed of two side plates C, adjacent to the respective sides of the machine, 45 and tie-pieces C', uniting these plates. There are also intermediate longitudinal plates C² in the frame. Mounted in bearings at the respective ends of the shaker-frame are shafts D D, on which are fixed eccentrically-mounted 50 sprocket-wheels. I have shown four of these wheels on each shaft; but there may be more

or less than four. By preference the longer radii of adjacent wheels E on the same shaft will be oppositely arranged, as shown. On the sprocket-wheels E are mounted endless 55 chains F, and each chain is provided with numerous transverse flights or buckets G. In Fig. 2 only one chain is represented as furnished with flights; but all will be so provided. The flights are omitted from the other chains 60 in order to avoid unnecessary repetition and to avoid obscuring the drawings. In Fig. 1 only a few of the flights are shown for similar reasons. These flights serve to carry the straw and to prevent falling through the 65 shaker. The shaker and carrier is driven through the medium of the upper shaft D, and this latter may be driven through the medium of pulleys and belts from the motor-shaft of the thrashing-machine.

It will be readily understood that while the wheels E operate to propel the chains F, and thus carry the straw upward and outward, the eccentricity of the said wheels will impart a certain lateral vibration to the chains which 75 will thoroughly shake the straw in its upward travel.

In order to impart an additional lateral vibration to the chains at or near the middle parts thereof, I mount under the upper strand 80 of each chain F a wheel F², rotatively mounted in forks or arms projecting radially from a rock-shaft F', which shaft is journaled in the plates C. The shaft F' is rocked by means of a crank F³ on the upper shaft D, which is 85 coupled by a link F⁴ to an arm F⁵ on the shaft F'. This construction is best illustrated in Fig. 3. After leaving the shaker the straw falls on a delivery endless apron H.

While it is not essential that the frame of 90 the shaker be made movable and adjustable or that said frame shall have any special construction, I prefer to, and usually do, mount said frame pivotally on the sides c of the thrashing-machine. This may be effected by 95 providing the side plates C with exteriorly-projecting trunnions d and furnishing the latter with bearings on the upper edge of the sides c. This construction enables the inclination of the shaker to be varied without difficulty.

In order to prevent the straw from wrap-

ping about the shafts D, shields D' may be employed. These may be made of sheet metal, secured to the ties C' and slotted to embrace the eccentric wheels E. The free end of the shield is curved so as to house the upper side of the shaft. Only a portion of one of these shields is seen in Fig. 2.

The chain of the delivery-apron consists of rectangular links R, arranged to overlap to an extent sufficient to enable the branches of the U-shaped hinge-piece R' to be passed up through them, so as to hinge them together. The flight G is secured between the said branches, as clearly shown. If it is not desired to employ a flight at every short link, the ends of the branches of the piece R' may be bent or clinched over the links, as seen at R³. This is the kind of chain I employ by preference for the chains F in my shaker.

Having thus described my invention, I claim—

1. In a thrashing-machine, the combination, to form a straw carrier and shaker, of the sprocket - wheel shafts, the eccentrically-mounted sprocket-wheels fixed thereon, the endless chains mounted on said wheels and provided with flights, and the intermediate

vibrator consisting of the rock-shaft, mechanism for rocking the same, and the wheels F², mounted on arms that radiate from said shaft; 30 said wheels being arranged under the respective chains of the carrier and the eccentric sprocket-wheels being arranged in the order set forth.

2. In a thrashing-machine, the combination, 35 with the frame of the shaker pivotally mounted on the machine-frame, whereby its inclination may be varied, of the sprocket-wheel shafts mounted in said frame, the sprocket-wheels mounted eccentrically on said shafts, 40 and the endless chains with flights mounted on said wheels, substantially as set forth.

3. The endless chains F of a straw-carrier, each consisting of overlapping links R, U-shaped hinge-pieces R', and flights G, the 45 flight being embraced between the branches of the hinge-piece, as set forth.

In witness whereof I have hereunto signed my name in the presence of two subscribing witnesses.

ERIK GUSTAF NICOLAUS SALENIUS.
